United States Patent Office

Des. 192,642
Patented Apr. 24, 1962

192,642

CARAFE

David Douglas, % David Douglas & Co. Inc.,
1332 S. 26th St., Manitowoc, Wis.

Filed Aug. 18, 1958, Ser. No. 52,233

Term of patent 7 years

(Cl. D44—21)

Fig. 3

Fig. 2

FIG. 4

FIG. 5

FIG. 1

FIG. 1 is a view in front elevation of a carafe embodying my new design;

FIG. 2 is a view in rear elevation;

FIG. 3 is a view in side elevation;

FIG. 4 is a top plan view thereof; and

FIG. 5 is a sectional view through the cover of such carafe.

I claim:

The ornamental design for a carafe, as shown.
